(57) **CLAIM**

The ornamental design for an irrigator, as shown and described.

DESCRIPTION

FIG. 1 is a right rear isometric view of an irrigator showing our new design;

FIG. 2 is a front left isometric view thereof;

FIG. 3 is a front elevational view thereof;

FIG. 4 is a rear elevational view thereof;

FIG. 5 is a right side elevational view thereof, the left side elevation being a mirror image;

FIG. 6 is a top view thereof; and,

FIG. 7 is a bottom view thereof.

The broken lines in the drawings illustrate portions of the irrigator that form no part of the claimed design.

1 Claim, 3 Drawing Sheets
